United States Patent Office

Des. 188,095
Patented June 7, 1960

188,095

VACUUM CLEANER

Ralph C. Osborn, 3007 E. Oakland Road,
Bloomington, Ill.

Filed June 8, 1959, Ser. No. 56,251

Term of patent 14 years

(Cl. D9—2)

Fig. 1.

Fig. 2.

Fig. 3.

Fig. 4.

Fig. 5.

Figure 1 is a front perspective view of a vacuum cleaner showing my new design;

Figure 2 is a rear perspective view thereof;

Figure 3 is a top view thereof;

Figure 4 is a side elevational view thereof; and

Figure 5 is a rear elevational view thereof.

I claim:

The ornamental design for a vacuum cleaner, substantially as shown.

References Cited in the file of this patent

UNITED STATES PATENTS

D. 180,231 Hillgren ----- May 7, 1957
 D. 183,766 Petrie ----- Oct. 21, 1958

OTHER REFERENCES

Sears, Roebuck catalog, spring and summer 1958, page 885, at upper right of page, Silvertone, 6 transistor portable radio, and page 894, at upper left of page, Kenmore vacuum cleaner.

Electrical Merchandising, May 1958, page 24, lower left of page, Whirlpool Bambi vacuum cleaner.